E. S. WILKINS AND JOHN STRAW, OF STOWE, VERMONT.

Letters Patent No. 63,973, dated April 16, 1867; antedated March 14, 1867.

IMPROVED MOP SQUEEZER.

The Schedule referred to in these Letters Patent and making part of the same.

TO ALL WHOM IT MAY CONCERN:

Be it known that we, E. S. WILKINS and J. STRAW, of Stowe, Lamoille county, and State of Vermont, have invented a new and useful Mop Squeezer with treadle and spring lever combined; and we do hereby declare the following to be an exact description thereof, reference being had to the accompanying drawings, and to the letters of reference marked thereon, making a part of this specification, in which—

Figure 1 represents a top view of the machine; and

Figure 2 a longitudinal section.

The nature of our invention consists in the treadle mop squeezer and spring lever and pail, as arranged and combined as follows:

A small frame, A, is attached to a common pail, B, by an adjustable hoop or ears, C, as we may choose. Attached to this frame A are two side-boards, D D, hung and operating at one end on a roller, E, with a press-board, G, between them, and made firm to the side-boards D. The other press-board H is attached to the side-boards D by a round tenon, J, on the lower edge, which slides in a mortise, K, in the side-boards, with rubber springs L to assist in the pressure. The board H is confined at the other end of the frame by a tapering lever, M, fastened to the press-board H at one end, and at the other end operating in the roller N that is across the frame A. On this lever M is a coiled wire spring, P, which presses against the roller N so as to throw up and open the press-boards G and H. At one end of the side-boards D is attached a treadle, R, to place the foot on and press down the side-boards D and close the press-boards G and H together, and between which the mop is squeezed and cleansed.

We do not claim press-boards or a treadle and spring lever as commonly used, but what we claim as our invention, and desire to secure by Letters Patent, is—

The treadle R, mop squeeze G and H, and spring lever M and pail B, when arranged, combined, and operated as herein described, and for the purposes set forth.
